AGITATING, AERATING, AND/OR MIXING
MACHINEJames Joseph Bean, Salt Lake City, Utah, assignor
to American Cyanamid Company, New York,
N. Y., a corporation of Maine

Application October 23, 1937, Serial No. 170,551

3 Claims. (Cl. 259—96)

This invention relates to an improved aerating machine and particularly to improved aerating machines suitable for the froth flotation of minerals.

5 In the past mechanical aerating machines in which air is beaten into a liquid or pulp by mechanical means have gradually superseded the older and less efficient types of machines particularly in the froth flotation of minerals. Most 10 of the mechanical machines are provided with rotating elements to beat in air and in some of the machines, notably the Fagergren machine, the rotating element which is in the form of a squirrel cage composed of vertical staves is surrounded partly or completely by a stator of similar construction.

The high efficiency of the mechanical machines and particularly those of the Fagergren type has been coupled with a certain lack of flexibility in changing from one ore to another. This 20 has been a particular problem in the case of laboratory flotation machines and those which are used in experimental or pilot plants or plants where the minerals to be floated are frequently changed. This lack of flexibility is due to the fact 25 that the rotor and stator assembly in the Fagergren type of machine and similar elements in other mechanical machines using rotating agitators are rigidly mounted and in order to make 30 changes or small repairs on the element, it has been necessary to shut down the machine and to disassemble the parts in question. In the case 35 of some laboratory machine of the Fagergren type, a certain flexibility has been obtained by using a removable flotation chamber which can be lowered from contact with the agitating elements and cleaned out. However, it is still necessary to clean the agitating elements when changing 40 from one mineral to another and this is a weakness and time-consuming element of the laboratory machines. It is also desirable at times to change the aerating compartment and this could not be done without disturbing the agitating elements.

45 The present invention provides for complete elimination of difficulties encountered in removing agitating elements and at the same time retains all of the advantages of the firm and rigid stand, individual electric drive and the like, which 50 are notable characteristics of many of the most successful mechanical machines including particularly the Fagergren type of machine. The invention will be more particularly described in conjunction with a machine of the Fagergren type although its principle is applicable to other

machines having rotating agitators. Particularly, the invention provides for a linkage which permits withdrawing the agitating element from the machine without dismounting the machine and even, if desirable, without shutting it down. A 5 simple tilting is usually not practical because the clearance between the agitating element and the flotation chamber walls is normally insufficient to permit swinging the agitating element up in an arc.

10 According to the present invention the agitating elements are mounted on a suitable frame or housing which is provided with a linkage permitting it to be raised substantially vertically for a sufficient distance to clear the top walls of the 15 flotation chamber and then to tilt in an arc to completely expose the agitating elements. The invention will be described in detail in conjunction with a very simple type of linkage. It should be noted, however, that the invention in its broader aspects is not limited to the particular design 20 of linkage shown but any other linkage permitting the same mechanical movement may be substituted. The invention will be described in detail in conjunction with a machine of the Fagergren type, adapted for laboratory use. The details of the invention are, of course, equally applicable to larger machines. It is an advantage 25 that the operating characteristics of the machine are in no way altered by the inclusion of the improvement of the present invention.

30 In the drawings,

Fig. 1 is a plan view of the machine;

Fig. 2 is a side view of the machine in operating position;

Fig. 3 is a side elevation of the machine with the agitating elements in a fully lifted position;

Fig. 4 is an enlarged detailed elevation of the linkage mechanism, partly broken away, showing the portion in section along the line 4—4 of Fig. 40 1; and

Fig. 5 is an enlarged vertical section through the flotation chamber and agitating mechanism, the section being taken along the line of 5—5 of Fig. 2.

45 The machine illustrated in the drawings, which is a laboratory type of Fagergren machine, consists of a frame 1 on which is mounted a table 2 which can be moved vertically on a slide through which its clamping bolts 3 extend. On the shelf 4 is mounted the flotation chamber 5 having a froth overflow lip 8. An agitator housing 6 extends into the flotation chamber in the operative position (shown in Fig. 2), and carries in its lower end a stator formed of the staves 12 which 55

may, if necessary, be provided with a rubber covering. The housing also carries a pet-cock 22, the opening of which can be adjusted to vary the amount of air beaten into the ore pulp during the operation of the machine. Inside the housing is a shaft 13 carrying the rotor staves 14 and being journaled in the large upper portion of the housing that contains the ball bearings 15. The top of the shaft is provided with a pulley 7 which is driven from the motor 10 by the belt 11. The housing itself is integral with a hollow arm casting 9 on which the motor 10 is bolted. In this arm are pivoted two links 16 and 17, the latter being considerably longer than the former. The other end of the link 17 is mounted on the pin 18 in the framework 1 and the further end of the link 16 is keyed to a shaft 19 also journaled in the framework 1 (see Fig. 4). The shaft 19 can be rotated by its crank 20. In operating position the arm 9 is horizontal, resting on the top of the framework 1. The pivot of the link 16 fits into a semi-circular groove 21 on the frame 1. In this position the rotor and stator elements are near the bottom of the flotation chamber, the clearance being adjustable by a small vertical movement of the table 4. The operation of the machine is then the same as in a typical Fagergren machine in which the rotor and stator are rigidly and permanently mounted. When it is desired to change to another ore or for any reason to inspect or repair the agitating elements, the crank 20 is rotated in the direction shown by the arrow in Fig. 2. This causes the short link 16 to be rotated about the shaft 19 and raises the arm 9 substantially vertically because of the fact that the link 17 does not permit the arm 9 to describe an arc during the first portion of the movement, the agitating element being moved substantially vertically until it can clear the top of the flotation chamber. At this point, which is determined by the relative length of the links 16 and 17, the arm 9 begins to tilt and finally assumes the position shown in Fig. 3 in which the agitating elements are entirely clear of the flotation chamber. In a laboratory machine when it is desired to run another batch, the material adhering to the rotor and stator is washed out with a small stream of water, a tailings analysis made on the contents and the container either returned or replaced by another container with a fresh charge. The crank is then rotated in the opposite direction to return the agitating elements into chamber 5 in the position shown in Fig. 2, at which time the motor 19 may be started and another batch run.

While the present invention is particularly important in the laboratory machine where numerous batches of ores are run, it is also advantageous in larger machines for pilot plants or actual production. Of course, in such machines the design of the flotation chamber is suitably altered to provide for continuous inlet and discharge of pulp and permit connection of the overflow lip to froth launders. The design in the case of the Fagergren machine is clearly shown in the Fagergren Patent No. 1,963,122 dated June 19, 1934, and it is an advantage of the present invention that no serious change in the operation of the machine is necessary. In other words, the present invention operates with the same efficiency as a standard Fagergren machine and yet permits rapid removal of rotor and stator without requiring the machine to be taken out of circuit. This is important in many production installations where a relatively long string

of machines operates in series. Thus, for example, in a string of 8 to 10 machines, it is readily feasible to take out one machine without seriously affecting the metallurgy and repairs to the rotor and stator can be made without shutting down the whole string.

Another important advantage is noted when operating with extremely thick pulps or with very coarse feed which may cause sanding. If the pulp is too thick for an ordinary machine, it is not easy to start up the machine although the power available may be sufficient to keep it running once it is started. By means of the present invention it is possible to raise the rotor and stator somewhat above the position on the bottom of the flotation compartment, which greatly decreases the starting torque required, to start the motor and gradually lower the elements. This makes it possible to use a motor with a smaller overload capacity which means greater economy and in the case of coarse feed or sticking of the agitating mechanism, it is possible to rapidly lift the agitator and remove any obstruction.

The same possibility of moving the agitator while the motor is running is likewise of importance with a machine to be used for economical agitation of very viscous materials. It is possible to start the machine with the agitator partly raised and gradually lower it into position.

Another important advantage of the present invention in production machines lies in the possibility of slight vertical movement of the agitating mechanism in order to vary the clearance between the agitator and the bottom of the flotation compartment. This permits larger proportions of the aerated material to pass below the stator and reenter the agitator and increases the per cent of recirculation. This is particularly advantageous in machines which are to be used for pilot plants since it is possible to experiment with different degrees of recirculation without changing the design of the machine. Also variations of the ore feed in installations may require for best flotation efficiency a varying degree of recirculation which can be taken care of by slight vertical displacement of the agitator column.

The laboratory machine shown in the drawings is provided with a simple hand crank for operating the linkage. Of course, in a larger machine the weight of the agitation mechanism is too great to permit the use of the simple hand crank and gearing is required in order to move the linkage. A suitable reduction gearing can, of course, be interposed between the crank and the shaft 19. For laboratory machine use and in many cases for pilot plant use, a belt drive such as is shown in the drawings is advantageous as it permits varying speeds by changing the pulleys. However in large production machines it is often desirable to use a positive drive such as gear train, direct drive, or the like. The type of drive, of course, is not limited to the particular form shown in the drawings.

In the case of pilot plant and production machines where it may be desired to vary the clearance between the agitating mechanism and the bottom of the flotation chamber, it is frequently desirable to associate a suitable scale and indicator with the shaft 19 so that the clearance can be read directly and any desired clearance obtained immediately. Such a scale, of course, in no way changes the operation of the invention.

It should be also understood that in larger machines standard accessories, such as froth skimmers, etc., can be employed. The present

invention does not alter the construction of the rest of the machine and, of course, such standard equipment is not illustrated as it is not necessary for a laboratory machine such as is shown in the drawings.

5 What I claim is:

1. In an aerating machine provided with a rotating agitating element suspended in an aerating chamber, said chamber having at all points 10 above the agitating means a periphery greater than the outside periphery of the agitating means, a housing supporting said agitating means from the top, said housing being provided with a horizontal arm above the aerating chamber 15 and supported by a vertical framework at the side of said aerating chamber, the improvement which comprises connecting said arm to said framework through two links of unequal length, the short link being pivoted in the horizontal arm and keyed at its other end to a shaft journaled in the frame, means for rotating said shaft, the two links being so positioned when the agitating ele- 10
